UNITED STATES PATENT OFFICE.

FRED D. HOLDSWORTH, OF CLAREMONT, NEW HAMPSHIRE, ASSIGNOR TO SULLIVAN MACHINERY COMPANY, A CORPORATION OF MASSACHUSETTS.

CONTROLLING MECHANISM FOR COMPRESSORS.

Application filed April 27, 1917. Serial No. 165,006.

To all whom it may concern:

Be it known that I, FRED D. HOLDSWORTH, a citizen of the United States, residing at Claremont, in the county of Sullivan and State of New Hampshire, have invented certain new and useful Improvements in Controlling Mechanisms for Compressors, of which the following is a full, clear, and exact specification.

10 My invention relates to controlling mechanisms for compressors.

It has for its object to provide an improved controlling mechanism for compressors or the like, whereby when the pressure developed thereby has exceeded a predetermined limit the compressor is automatically unloaded and again loaded when the pressure has dropped below a predetermined limit. A further and more specific object of 20 my invention is to provide improved means for accomplishing the above objects, especially adapted to use in connection with inlet valves of the suction type, the same having improved means whereby all delay in 25 the seating of said valves when the compressor is to be loaded is effectually overcome.

In the accompanying drawings, I have shown for purposes of illustration one embodiment which my invention may assume 30 in practice.

In these drawings,—

Fig. 1 is a side elevation of a compressor system equipped with my improvement, a portion of the compressor cylinder being 35 broken away to facilitate illustration.

Fig. 2 is an enlarged view of the regulator shown in partial section.

Fig. 3 is a further enlarged detail of the exhaust controlling valve mechanism for 40 the regulator.

In this illustrative construction, I have shown a compressor 1 which may be of any standard construction, equipped with a cylinder 2 and a piston 3 and having air supplied to its cylinder through suction inlet valves 4 and discharged therefrom through suitable discharge valves 5 and through a pipe connection 6 leading to a receiver 7. As shown, the inlet valves 4 are provided 45 with stems 8 normally held in projected position by means of springs 9 in such a manner as to seat the valves. Disposed beneath these valves are also cylinders 10 in which move pistons 11 adapted to engage the stems 50 of the valves and lift the same from their

seats when pressure is supplied to the pistons through a pipe connection 12.

In my improvement, I have provided an improved regulator disposed in the pipe connection 12 and connected between the same 60 and a pipe connection 13 leading to the receiver. This regulator, as shown, comprises a casing 14 having an inlet 15 connected to the receiver connection 13 and an outlet 16 connected to the valve connection 65 12. In the form illustrated, this regulator is also provided with a cylinder 17 in which is disposed a piston 18 normally held in depressed position by a coiled spring 19, the tension of which is adjustable by means of 70 a threaded adjusting nut 20 threaded in the upper end of the cylinder. Upon the lower end of this piston 18 is also carried a valve or pin 21, herein having a conical point, adapted to be received in a suitable round 75 orifice 22 in the bottom of the cylinder, which is shown herein as located in a plane below the inlet 15. As illustrated, this orifice 22 opens into a lower chamber 23 having communication with the outlet 16. 80 Within this chamber 23 is also carried a threaded plug 24 having threaded upon its reduced upper end 25 a valve housing 26 provided with one or more lateral orifices 27 communicating with the outlet 16 and a 85 central orifice 28 opening under the orifice 22. Within this valve housing 26 is also carried a valve 29, preferably in the form of a plate or disc, normally held in elevated position by means of a coiled spring 30 90 housed within an axial chamber 31 in the plug 24. As shown, this valve 29 is also provided with a leakage orifice 32 therein adapted to permit the leakage of pressure fluid through the same and through the 95 spring chamber 31 to an outlet passage 33 disposed coaxially with the plug 24 and communicating with the atmosphere.

In the operation of my improved regulator, it will be noted that when the pressure in the receiver 7 rises above a predetermined point, the same will act upon the bottom of the piston 18 in such a manner as to raise the same from the position shown in Fig. 2. As this piston moves upward, 100 obviously, the valve 21 will be lifted, and as the latter is lifted the pressure will be enabled to act upon the surfaces forming the conical end thereof in such a manner as to give an additional upward impetus to the 105 110

piston. Thus, a supply of pressure fluid will be free to pass from the receiver through the inlet 15 and the orifice 22 in such a manner as to depress the disc valve 29 against the action of its spring 30 and permit the pressure fluid to flow through the orifice 28 and out through the lateral orifices 27 in the valve housing 26 to the outlet 16, through which it passes to the pipe connection 12 in order to act on the plungers 11 and raise the suction valves 4 from their seats to unload the compressor. Obviously, so long as the pressure in the receiver exceeds a predetermined amount, the same will 10 thus act upon the suction valves and hold the same from their seats in such a manner as to hold the compressor unloaded. It will be noted, however, that due to the leakage port 32 in the disc valve 29, a certain amount 15 of air beneath the plungers 11 will be escaping all the time through this leakage port and the passage 33 to the atmosphere. When, moreover, the pressure in the receiver drops below a predetermined limit, the piston 18 will be lowered due to the action of its spring 19, in such a manner as to close the orifice 22 and thus shut off the supply 20 of air to the valve pistons 11. After this occurs, there will be a short period of leakage 25 through the leakage port 32 in the valve 29 before the pressure in the pipe connection 16, 12 etc. becomes less than the pressure of the spring 30. When, however, this pressure has been depleted through this leakage, 30 and the spring becomes sufficiently powerful to throw the valve 29, it will lift this valve to the position shown in Fig. 3 and by so doing open the pipe connections 12 to the atmosphere through the ports 27 and 33. 35 As a result, the air in the pipe connections 12 and beneath the plunger 11 will be exhausted therefrom with a rush and the valves 4 will be seated very quickly. Obviously, this sequence of operation will be 40 repeated in accordance with variations in pressure in the receiver 7.

In the use of my improved construction, it will be noted that due to the provision of my improved means, whereby a certain amount of leakage is permitted from beneath the suction valve operating pistons and the exhaust controlling valve is then thrown in such a manner as to open wide the communication to the atmosphere, the suction valves are caused to close with a decidedly quick movement as distinguished from any such delayed closing movement of the same as would result in a loss of efficiency of the compressor. It will also be noted that an exceedingly simple and cheap construction is produced, it only being necessary to machine a single cylinder. If desired, even this cylinder, under certain conditions, may be roughly bored, an expandable cupped washer 34 then being suit-

ably clamped on a reduced end 35 of the piston 18, as by means of a washer 36 and bolt 37. These and other advantages of my improvement will, however, be apparent to those skilled in the art.

While I have in this application specifically described one embodiment which my invention may assume in practice, it is of course to be understood that the invention may be modified and embodied in various other forms without departing from its spirit, it being my intention to include all such modifications within the scope of the appended claims.

What I claim as new and desire to secure by Letters Patent is:

1. The combination with a compressor, of a fluid operated unloading mechanism, and controlling means therefor for varying the exhaust therefrom without interrupting it.

2. The combination with a compressor, of a fluid operated unloading mechanism, and controlling means therefore for automatically varying the exhaust therefrom without interrupting it.

3. The combination with a compressor, of a fluid operated unloading mechanism, and controlling means therefor for increasing the exhaust therefrom during the loading of the compressor without interrupting it.

4. The combination with a compressor having a discharge pipe and fluid pressure operated unloading mechanism, of a compressor controlling means comprising a conduit connecting said pipe and said unloading mechanism, and means in said conduit for controlling a flow of pressure fluid to said unloading mechanism, for maintaining the pressure of the fluid in said mechanism substantially constant during the unloading of the compressor, and for providing an accelerated uninterrupted exhaust for the pressure fluid from said mechanism when said compressor is to be loaded.

5. The combination with a compressor having a discharge pipe and fluid pressure operated unloading mechanism, of a compressor controlling means comprising a conduit connecting said pipe and said unloading mechanism, and means in said conduit for controlling a flow of pressure fluid to said unloading mechanism, for permitting a slow exhausting of pressure fluid from said mechanism during the unloading of the compressor, and for automatically accelerating the exhaust of the pressure fluid, without interrupting the same, from said mechanism when said compressor is to be loaded.

6. In a compressor controlling mechanism, in combination, a compressor, one or more inlet valves therefor, a receiver connected to said compressor, pressure actuated mechanism for actuating said inlet valves, a fluid connection between said receiver and said mechanism, a pressure controlled valve

- controlling said connection, and a cooperating valve between said valve and said inlet valve actuating mechanism operative upon opening of said first mentioned controlling valve to provide a small exhaust connection in communication with said inlet valve actuating mechanism, and after closing of said first mentioned valve to open a supplemental exhaust connection.
- 10 7. In a compressor controlling mechanism, in combination, a compressor, one or more inlet valves therefor, a receiver connected to said compressor, pressure actuated mechanism for actuating said inlet valves, a fluid connection between said receiver and said mechanism, a pressure controlled valve controlling said connection, and a cooperating valve between said valve and said inlet valve actuating mechanism operative upon opening of said first mentioned controlling valve to provide a small exhaust connection in communication with said inlet valve actuating mechanism, and after closing of said first mentioned valve to open a supplemental exhaust connection which remains open until said controlling valve again reopens.
- 15 8. In a compressor controlling mechanism, in combination, a compressor, one or more inlet valves therefor, a receiver connected to said compressor, pressure actuated mechanism for actuating said inlet valves, a fluid connection between said receiver and said mechanism, a pressure controlled valve controlling said connection, and valve means between said valve and said inlet valve actuating mechanism comprising a cooperating valve operative upon opening of said first mentioned controlling valve to provide a small connection with the exhaust in communication with said inlet valve actuating mechanism, and upon closing of said first mentioned valve to open a supplemental exhaust connection while said initial connection remains open.
- 20 9. In a compressor controlling mechanism, in combination, a compressor, one or more inlet valves therefor, a receiver connected to said compressor, pressure actuated mechanism for actuating said inlet valves, a fluid connection between said receiver and said inlet valve actuating mechanism, a pressure controlled valve controlling said connection, an exhaust port in said connection, and auxiliary valve means operative in opposite positions to provide a limited connection with said exhaust or a relatively large connection with said exhaust and movable from one position to the other without interrupting communication between said mechanism and the exhaust.
- 25 10. A controlling valve for use in compressor unloading mechanisms comprising a casing, a ported partition therein, a connection for compressor discharge pressure on one side of said partition and a connection for compressor unloading mechanism actuating means on the other side of said partition, a pressure controlled valve on one side of the partition controlling the port in said partition, an exhaust port on the opposite side of said partition, a cooperating valve operative in opposite positions to seat over said exhaust port and provide a limited exhaust therethrough or to uncover said exhaust port entirely, and a port communicating with the connection for unloading mechanism actuating means across which said valve moves and of greater length than the length of said valve in the direction of its movement.
- 30 11. In a compressor controlling mechanism, in combination, a compressor, one or more inlet valves therefor, a receiver connected to said compressor, a connection between said receiver and said inlet valves, pressure actuated plunger mechanism disposed in said connection for actuating said inlet valves, a valve controlling said connection, and means including a second valve constantly communicating with the atmosphere operative after the closure of said first named controlling valve and a predetermined drop in pressure in a portion of said connection to provide an accelerated exhaust of the air beneath said plunger mechanism without interrupting said exhaust.
- 35 12. In a compressor controlling mechanism, in combination, a compressor, one or more inlet valves therefor, a receiver connected to said compressor, a connection between said receiver and said inlet valves, pressure actuated plunger mechanism disposed in said connection for actuating said inlet valves, a valve controlling said connection and responsive to variations in receiver pressure, and means including a cooperating valve in said connection opened by receiver pressure after opening of said first mentioned controlling valve and operable after the closure thereof to provide an accelerated exhaust of the air beneath said plunger without interrupting said exhaust.
- 40 13. In a compressor controlling mechanism, in combination, a compressor, one or more inlet valves therefor, a receiver connected to said compressor, a connection between said receiver and said valves, pressure actuated plunger mechanism disposed in said connection for actuating said inlet valves, a valve controlling said connection and responsive to variations in receiver pressure, and a cooperating valve in said connection having an opening therein constantly communicating with the atmosphere, said valve being opened by receiver pressure after opening of said first mentioned controlling valve and operable after closure of the latter and a predetermined pressure drop in a portion of said connection to provide accelerated exhaust.

ated exhaust of the fluid in said portion without interruption of the exhaust therefrom.

14. In a compressor controlling mechanism, in combination, a compressor, one or more inlet valves therefor, a receiver connected to said compressor, a connection between said receiver and said valves, pressure actuated valve actuating mechanism disposed in said connection, a valve mechanism normally closing said connection and responsive to variations in receiver pressure, and a cooperating valve mechanism responsive to receiver pressure upon opening of said first mentioned controlling valve mechanism and operable after closure thereof and a predetermined drop in pressure in a portion of said connection leading to said actuating mechanism to open a free communication longitudinally of said valve between said portion and the atmosphere.

15. In a compressor controlling mechanism, in combination, a compressor, one or more inlet valves therefor, a receiver connected to said compressor, a connection between said receiver and said valves, pressure actuated valve actuating mechanism disposed in said connection, a valve mechanism normally closing said connection and responsive to variations in receiver pressure, and a cooperating valve mechanism responsive to receiver pressure upon opening of said first mentioned controlling valve mechanism and forming a constant communication with the atmosphere operative after closure of said first mentioned controlling valve mechanism and a predetermined drop in pressure in a portion of said connection leading to said actuating mechanism for opening, without interruption of the exhaust, an enlarged exhaust for the air within said portion.

16. In a compressor controlling mechanism, in combination, a compressor, one or more inlet valves therefor, a receiver connected to said compressor, a connection between said receiver and said valves, pressure actuated mechanism disposed in said connection for actuating said inlet valves, means forming a port in said connection, a valve responsive to variations in receiver pressure controlling communication through said port, and a cooperating valve mechanism disposed on the opposite side of said port and responsive to receiver pressure upon opening of said second mentioned valve and to a drop in pressure when the latter is closed for effecting a varied but uninterrupted communication between said inlet valve actuating mechanism and the atmosphere.

17. In a compressor controlling mechanism, in combination, a compressor, one or more inlet valves therefor, a receiver connected to said compressor, a connection between said receiver and said valves, pressure actuated mechanism disposed in said connection for actuating said inlet valves, means forming a port in said connection, a valve responsive to variations in receiver pressure controlling communication through said port, and a cooperating valve mechanism forming a constant communication with the atmosphere and disposed on the opposite side of said port and responsive to receiver pressure upon opening of said first mentioned controlling valve and operable upon a predetermined drop in pressure in a portion of said connection after closure of said first named controlling valve to open, without closure of said first mentioned communication, free communication between said inlet valve actuating mechanism and the atmosphere.

18. In a compressor regulator, in combination, a valve casing having a plurality of chambers therein, one provided with an inlet and the other provided with an outlet, a valve reciprocable in one of said chambers and having a conical end, means forming a division wall between said chambers and having a port therein in which the conical end of said valve is normally seated, a ported valve member coaxial with said last mentioned valve located on the opposite side of the division wall and in the other of said chambers having constant communication with the atmosphere, and means forming an enlarged port normally closed by said last mentioned valve and providing a communication between said chamber and the atmosphere in a predetermined position of said valve.

19. A compressor regulator having a chamber adapted for communication with a compressor, a valve to control communication between the compressor and said chamber, and a separate, independently-operable relief valve complementary to said chamber and constructed and arranged to remain open until the first valve has opened a predetermined distance and to then be closed to practically close communication with the atmosphere and also constructed and arranged to remain closed until the pressure is reduced to a predetermined extent and to then promptly open and afford free communication to the atmosphere, whereby positive action of the regulator is insured.

In testimony whereof I affix my signature.
FRED D. HOLDSWORTH.
